UNITED STATES PATENT OFFICE

100,050

DESIGN FOR A BOTTLE

James C. Sheridan, San Francisco, Calif., assignor to Carr-Lowrey Glass Co., Baltimore, Md.

Application February 18, 1936, Serial No. 61,230

Term of patent 14 years

To all whom it may concern:

Be it known that I, James C. Sheridan, a citizen of the United States, residing at San Francisco, in the county of San Francisco and State of California, have invented a new, original, and ornamental Design for a Bottle, of which the following is a specification, reference being had to the accompanying drawing, forming part thereof.

I claim:—

The ornamental design for a bottle, as shown.

JAMES C. SHERIDAN.
